Dr. J. L. Tastenatty

UNITED STATES PATENT OFFICE.

PERLEY E. FOX, OF MARLOW, NEW HAMPSHIRE.

HEATING-DRUM.

SPECIFICATION forming part of Letters Patent No. 325,405, dated September 1, 1885.

Application filed March 30, 1885. (No model.)

To all whom it may concern:

Be it known that I, PERLEY E. FOX, a citizen of the United States, residing at Marlow, in the county of Cheshire and State of New Hampshire, have invented certain new and useful Improvements in Heating-Drums; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

This invention relates to an improvement in heating-drums to be attached to stoves, furnaces, or other heating arrangements; and it consists of a double sheet-iron cylinder having a crescent-shaped draft-passage, constructed and arranged as hereinafter more fully described.

In the annexed drawings, illustrating the invention, Figure 1 is a front elevation of the device. Fig. 2 is a vertical section. Fig. 3 is a plan view of a flanged coupling piece or head which connects the cylindrical drum with the conical pipes at either end. Fig. 4 is a cross-section on the line *x x* of Fig. 2, and Fig. 5 is a vertical section on *y y* of Fig. 3.

Like letters of reference designate like parts in the several views.

A represents a double cylinder or drum, to both ends of which, by means of flanged coupling pieces or heads *C*, are secured conical caps or pipes *B B'*, which serve to connect the heater with the stove, stove-pipe, or other heating arrangement below, and with the stove-pipe above. The drum *A* is made by first constructing a simple cylinder of a single piece of sheet metal riveted together at the juncture, next flattening this cylinder until the two sides are only about an inch apart, and then bending up the flattened cylinder into a double drum until the edges are brought to within two inches (more or less) of touching. Thus a crescent-shaped draft-passage, *b*, is formed, and an interior chamber, *D*, inclosed by said draft-passage, which communicates with the air in the room by the space (about two inches, more or less) which intervenes between the edges of the draft-passage. The whole surface

of the original drum is thus brought into contact with the heat passing upward from the source of heat below, and also with the atmosphere of the room, and irradiation can take place at every point. The drum *A* may be made of any desired size, and a correspondingly large amount of heat will be thrown out therefrom.

C designates the heads or flanged coupling-pieces, which serve to unite the drum *A* and the conical pipes *B* and *B'*, and which also form heads for the interior inclosure, *D*. This coupling-piece is shown in Figs. 3 and 5. The latter, being a vertical section of the lower head or coupler, indicates the various parts of its construction. *a* is the outer periphery of the head *C*, and is a rim or collar dividing a sheet-metal ring into two flanges, *c c*, which fit tightly, one into the drum and the other into the conical piece. The coupling-piece has a crescent-shaped opening, *b*, which allows it to fit over the draft-passage, and the plate *C* forms the head of the interior chamber, *D*. The coupling-pieces *C*, drum *A*, and conical pipes *B B'* are all securely fastened together by rivets.

The pipes *B B'* are preferably made of conical form, and are but tapering pieces of pipe to connect drum with collar of the stove or stove-pipe. By this contrivance a drum of large size is reduced to a size and form which may be readily applied to any size stove-pipe without disfiguring the appearance of the device.

If desired, the open side of the drum may be covered by a sheet-iron jacket, *E*, (shown by dotted lines in Fig. 1,) neatly fitted upon it, a space being left open at each end through which the air will pass into and from the drum, thereby producing a strong current of heated air, which will rapidly heat and equalize all the air in the room.

The heater is to be attached to the collar of the stove or pipe in the ordinary way. The heat then will pass upward through the crescent-shaped openings in the head *C* into the similar-shaped draft-passage, whence it radiates into the room, and also into chamber *D*, and thence into the room; then it passes upward and outward into the chimney.

It is evident, also, that my heater-drum may be attached to a stove-pipe near to or remote from the stove. Thus the heater can be con-

veniently located in a room at some distance from the stove itself, and such room will in this way be heated with facility.

Having thus described my invention, what 5 I claim as new, and desire to secure by Letters Patent, is—

1. A heater-drum consisting of the combination of the crescent-shaped drum A, having interior heating-chamber, D, the flanged coupling-pieces C C, the conical pipes B B', and the jacket E, substantially as shown and described.

2. In a heater-drum, the combination, with a drum having crescent-shaped draft-passage and interior chamber, of a jacket or plate 15 adapted to cover a part of the opening into said chamber to create a draft, substantially as and for the purpose described.

In testimony whereof I affix my signature in presence of two witnesses.

PERLEY E. FOX.
